UNITED STATES PATENT OFFICE.

ARTHUR WILLIAM WILDE, OF PHILADELPHIA, PENNSYLVANIA, ASSIGNOR
TO JOHN H. BROMLEY, JOSEPH H. BROMLEY, EDWARD BROMLEY, AND
WILLIAM H. BROMLEY, OF SAME PLACE.

DESIGN FOR A LACE CURTAIN.

SPECIFICATION forming part of Design No. 26,372, dated December 1, 1896.

Application filed October 27, 1896. Serial No. 610,228. Term of patent 7 years.

To all whom it may concern:

Be it known that I, ARTHUR WILLIAM WILDE, a subject of the Queen of Great Britain, residing in the city of Philadelphia, State of Pennsylvania, have invented and produced a certain new and original Design for Lace Curtains, of which the following is a full, clear, and exact description, reference being had to the accompanying drawing, forming a part of this specification.

My invention relates to the ornamentation of woven fabrics in which the ornamental pattern is produced in the weaving; and it consists of a woven design for a lace curtain, as illustrated in the said drawing, in which the leading and characteristic features are the border A along the bottom edge and one side

edge, the complete figure B B' at the base edge of the curtain, a series of repeats of the figures B B' in vertical series along one side edge of the curtain, the figures B B' along the base edge and vertical edge being mitered at C at the base end of the curtain.

Having thus shown and described my invention, I claim—

The design for a lace curtain substantially as shown and described.

In testimony whereof I have hereunto affixed my signature this 16th day of October, A. D. 1896.

ARTHUR WILLIAM WILDE.

Witnesses:

ADOLPH PETZOLD,
H. T. FENTON.
